(57) **CLAIM**

The ornamental design for a cleaning device, as shown and described.

DESCRIPTION

FIG. 1 is a front, top perspective view of a cleaning device according to the present disclosure;

FIG. 2 is a rear, bottom perspective view of the cleaning device of FIG. 1;

FIG. 3 is a first side view of the cleaning device of FIG. 1; FIG. 4 is a second, opposite side view of the cleaning device of FIG. 1;

FIG. 5 is a front view of the cleaning device of FIG. 1; FIG. 6 is a rear view of the cleaning device of FIG. 1; FIG. 7 is a top view of the cleaning device of FIG. 1; and, FIG. 8 is a bottom view of the cleaning device of FIG. 1. The broken lines in the drawings depict portions of the cleaning device that form no part of the claimed design.

A portion of the disclosure of this patent document contains material which is subject to trademark protection. This patent document may show and/or describe matter which is or may become a trademark of Unger Marketing International LLC. The trademark owner has no objection to the facsimile reproduction by anyone of the patent disclosure as it appears in the Patent and Trademark Office patent files or records, but otherwise reserves all trademark rights whatsoever.
